IRVING KEMP, OF NEW YORK, N. Y.

WINDOW GRATING

Application filed August 2, 1927. Serial No. 210,051.

This invention relates to window gratings.

One object of this invention is to provide an improved grating for a window or door, having removable bars held in place by a locking mechanism that anchors and reinforces the bars against any possible spreading, as by the use of a jimmy, crow-bar, or the like.

A further object of this invention is to provide a grating of the character set forth having individually removable bars and means to lock the bars in place and reinforcingly connect them together, so that the sawing of a bar or part of the locking means may be insufficient to afford entrance through the grate.

Still a further object of this invention is to provide a grating that can be rapidly assembled or disassembled and comprises an improved locking device formed of few and simple parts that coact to form a neat construction which is rugged and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a view in elevation of an embodiment of the invention applied to the interior side of a window in a door, with parts broken away to illustrate the internal construction of the locking mechanism.

Fig. 2 is a vertical sectional view taken on line 2-2 of Fig. 1.

Fig. 3 is a plan sectional view of the window and grating shown in Fig. 1, as seen along line 3-3.

Figs. 4 and 5 are horizontal sectional views taken on lines 4-4 and 5-5 respectively of Fig. 1.

Fig. 6 is a view corresponding to Fig. 1,

with the locking mechanism unlocked and removed, some of the bars being removed and showing a bar in the course of being removed.

Fig. 7 is an enlarged plan view of a modified locking mechanism for the bars of said grating. 55

Figs. 8 and 9 are vertical sectional detail views taken on lines 8-8 and 9-9 of Fig. 7, showing details of the improved locking 60 mechanism. 60

Figs. 10 and 11 illustrate a modified method of connecting the bars of the grating at the top portions of said bars.

Referring in detail to the drawings, 10 65 denotes a grating embodying the invention, shown applied on the interior side of any suitable frame 11 about any opening to be guarded, as, for instance, window 11^a. Said grating includes a plurality of vertical bars 70 12 removably supported upon the base section 14 of casing A and retained in vertical position by being received at their upper ends in the bracket 13, the bracket 13 and base section 14 being secured to frame 11 by 75 any suitable fastening means 15. The fastening means 15 securing bracket 13 to frame 11 are positioned as shown in Figs. 1, 2, and 6, so that they are inaccessible when bars 12 are supported in the grating. 80

The casing A is made up of the base section 14 and the cover section 16, the latter being removably received upon the former to retain the rods locked in position with respect to frame 11. The base section 14 is of angular 85 cross-section and is provided with end walls 17 preferably formed integral therewith. Formed in the horizontal portion 14^b of base section 14 are the recesses 20 into which the pins 19 formed on bars 12 are receivable. 90 End walls 17 and the vertical portion 14^c of base section 14 are provided with a flanged edge portion 14^d providing a shoulder 14^d upon which the edges of cover section 16 are adapted to be supported. End walls 17 are 95 provided with grooves 27 and horizontal portion 14^a is provided with an opening 23 adapted to cooperate with parts on cover section 16 in the hereinafter described manner.

Cover section 16 is of a cross-section simi- 100

lar to that of base section 14, the vertical portion 16^a thereof being provided with a tongue 22 positioned for reception through opening 23 when cover section 16 is properly associated with base section 14. Ribs 26 are formed along the ends of vertical portion 16^a and are preferably integral therewith. Said ribs are slidably received in grooves 27 when cover section 16 is positioned and serve to restrain said section from any horizontal movement. The tongue 22 has formed therein the perforation 25 through which, when tongue 22 has been passed through opening 23, a lock 24 may be engaged to prevent any vertical movement of section 16. When cover section 16 has been positioned on base section 14, a box-like structure is produced.

Bars 12, at their lower ends, are provided with the collars 18 positioned above pins 19 and fixed to bars 12 in any suitable manner. Pins 19 may be of the same thickness as bars 12 or, as shown here, preferably of a reduced diameter formed by undercutting the end of said bar.

Cover 16 is cut away or otherwise formed to provide the notches 21 which are of sufficient width to pass around the bars 12 easily, but of insufficient width to permit passage of collars 18.

When bars 12 have been properly arranged with pins 19 received in recesses 20, cover section 16 may be positioned over base section 14 with notches 21 receiving bars 12, the under surface of the horizontal portion 16^b being then in engagement with the upper surface of collars 18 and also resting on shoulder 14^d. At the same time, ribs 26 and tongue 22 are received in grooves 27 and opening 23 respectively.

To provide for reinforcing the bar structure against sidewise strain or deflection, in case an unwarranted attempt be made to enlarge the opening, a cross member 28, made of a flat strip of metal or the like is provided, located preferably on the interior side of the grating and mounted on said bars in a particular manner to permit removal therefrom only under certain predetermined circumstances. Bars 12 are provided with pins 29 extending laterally from said bars preferably at the mid-sections thereof, said pins being provided with heads 29^a for the purpose hereinafter appearing. Said cross member is formed with a group of notches 30 along its upper edge, the openings of said notches pointing upwardly, while another group of notches 31, cut or formed in the lower edge of cross-member 28 has the openings thereof pointing downwardly. It is to be understood that these notches need not be grouped in any particular manner on cross member 28, nor is there any necessary number relation involved in their mounting. A single notch 30 will effectively cooperate with a plurality of notches 31 and with the bars 12 to produce the

function desired. Various combinations of notches are therefore possible, so long as sufficient lower notches 31 are provided for effectively supporting the cross-member 28 with respect to bars 12, as hereinafter described. Pins 29 are adapted for sliding reception in notches 30, 31, the thickness of cross member 28 being slightly less than the distance between the head 29^a of pin 29 and bar 12. Notches 30, 31 are made of considerable depth to provide greater security against disengagement of pins 29 from member 28.

The bracket 13, of angular cross-section, is provided in the horizontal portion 13^a thereof with through holes 32 positioned to align with a notch 30 or 31, a notch 21, and a recess 20.

The assembly and manner of use of the device is easily made apparent from the following: One end of each bar 12 is passed upward through a hole 32 in the bracket 13 and then pin 19 of said bar is seated in recess 20 of casing A. For a more efficient assembly, bars 12 to be associated with notches 31 are first positioned in the grating with their pins 29 positioned for reception in notches 31. Bars 12 to be associated with notches 30 are mounted in a manner similar to the other bars, but with their pins 29 rotated to one side, as shown in Fig. 6. Cross-member 28 is now mounted on bars 12 with the respective pins 29 engaging the notches 31. By slightly lifting the bars 12 having pins 29 to engage notches 30 so that said pins are raised above the upper edge of cross-member 28, the bar 12 may be rotated so that said pin will be in alignment with, and if allowed to fall, will slide into notch 30.

After the bars have been thus arranged, cover member 16 may be positioned with notches 21 engaging bars 12 and collars 18 engaged by said member to retain bars 12 in a locked position upon engaging lock 24 with tongue 22.

It, of course, is understood that, if any of bars 12 are to be removed for any particular purpose, the reverse operation must be carried out.

Besides possessing the advantage of permitting the removal of any bar, as may be desired, said grating has excellent burglar proof qualities in that the sawing of any of the bars or cross member at any point does not result in any disengagement of the grating parts. Moreover, the grating is of simple manufacture and adapted for heavy and strong construction.

In Figs. 7 to 9 is illustrated the improved grating provided with a modified means for locking the cover section 116 to base section 114 in which plunger lock 33 is incorporated. Said plunger lock, preferably mounted interiorly of cover 116 and centrally on the horizontal portion 116^b thereof, is provided at an end thereof with a plurality of integral fingers 33^a to engage detachably in

recesses 34^a of a hub 34. Hub 34, which is rotatably mounted on any suitable pivot means as, for instance, machine screw 35, rigidly secured to horizontal wall 114^a of base section 114, is provided with arms 36 and 37 made integral therewith, or in any other manner secured thereto. Said arms extend outwardly from said hub into openings 40 provided in bolts 38, 39, with which 10 said arms are adapted to have sliding and pivotal connection. Said bolts rest on the base section 114^a of the casing, being slidably mounted at opposite sides of said section in guides 41, and movable in opposite directions 15 upon actuation of arms 36 and 37. When the bolts are projected, they engage with recesses 42 cut in lugs 43 and 44, the former of which comprises an inwardly extending edge portion 116^c on the vertical wall 116^a of cover 20 section 116, while the latter is provided by an arm 116^d extending down from the horizontal portion 116^b of said section. Both lugs 43 and 44 are at the ends of said cover section and in conjunction with the ribs 25 and grooves 127, ensure rigid connection of the cover section to the base section.

In Figs. 10 and 11, a construction is illustrated for use in connection with such bars 30 112 as are adapted to connect with a notch 31. In these cases, bars 112, preferably made with a flat end portion 45, are provided with a through opening 46 having extending upwardly therefrom the slot 47. Instead of 35 the extending horizontal portion 13^a of bracket 13, there is provided, in this modification, the pins 129, made integral with, or in any other suitable manner, secured to bracket 113, said pins having heads 129^a. 40 Opening 46 of bar 112 is adapted to be moved over head 129^a and then bar 112 allowed to fall so that slot 47 moves over pin 129. Downward movement as caused, for instance, by the use of a crow-bar, on the upper ends 45 of bars 112, is thereby effectually prevented.

It will thus be seen that there is provided a device in which the several objects of this invention are achieved, and which is well adapted to meet the conditions of practical 50 use.

As various possible embodiments might be made of the above invention, and as various changes might be made in the embodiment above set forth, it is to be understood 55 that all matter herein set forth or shown in the accompanying drawing is to be interpreted as illustrative and not in a limiting sense.

Having thus described my invention, I 60 claim as new and desire to secure by Letters Patent:—

1. A grating of the character described, comprising a plurality of bars, means to support said bars removably, and means to reinforce said bars, said means having means for

preventing longitudinal movement of said bars.

2. A grating of the character described, comprising a plurality of bars, means for anchoring said bars including a casing at one 70 end of said bars, and a cover member for said casing, said cover having openings for slidably receiving the bars in the casing, and means on said bars for coacting with said cover for restraining longitudinal movement 75 of the bars.

3. A grating of the character described, comprising a plurality of parallel bars, and anchor means therefor including an angular member having recesses formed to receive adjacent ends of said first mentioned bars, and an angular cover for said member and forming a casing therewith, said bars having means coacting with said cover to prevent withdrawal of said bars from said casing. 80

4. A grating of the character described, comprising a plurality of bars, an anchor casing for said bars, said casing having openings to receive portions of said bars, said bars having shoulder portions, said casing comprising 90 a member having openings to lock over said shoulder portions and prevent movement of said bars.

5. A grating of the character described, comprising a plurality of parallel bars, anchor means for said bars including an angular section to receive portions of said bars, said bars having shoulder portions, and an angular cover for said section adapted to form a casing therewith, said cover having 95 openings to receive said bars and being formed to lock over said shoulders, and means to fasten said cover to said section. 100

6. A grating of the character described, comprising a plurality of bars, anchor means 115 removably securing said bars, and a fixed cross member engaging said bars, said cross member being disengageable from said bars only when said bars are released from said anchor means.

7. A grating of the character set forth, comprising a plurality of parallel bars, means removably anchoring said bars, said bars having laterally extending pins, and a cross member having notches to removably engage said pins, said notches opening in different directions, as and for the purpose described and specified. 115

8. A grating of the character described, comprising a plurality of parallel bars, and anchor means therefor including an angular section having elements to receive adjacent ends of said bars, an angular cover for said section adapted to form a casing therewith, said bars having shoulder portions, said cover having openings to permit said cover to be received around said bars and over said portions, means to lock the cover to the casing, said bars having laterally extending headed pins, and a cross bar having notches opening 125 130

on different sides thereof to engage said pins.

9. A grating made up of removable bars, means for locking said bars against removal with respect to an opening to be guarded, said means including a cross member, and pins and notches associated with said bars and cross member.

10. A grating made up of removable bars, means for locking said bars in place in respect to an opening to be guarded, said means including a sectional casing mounted with respect to said opening, and means on said bars for cooperation with one section of said casing to restrain said bars.

11. A grating made up of removable bars, means for locking said bars in place in respect to an opening to be guarded, said means including a sectional casing mounted with respect to said opening, and means on said bars for cooperation with one section of said casing to restrain said bars, and means for locking said sections to each other.

12. In a grating made up of a plurality of movable bars, means secured to said bars to change the effective length of said bars, said means comprising a device for locking certain of said bars against vertical movement.

13. A grating of the character described comprising a casing, bars removably anchored in said casing, and single means for reinforcing all of said bars and simultaneously to lock all of said bars with relation to each other.

14. A grating made up of removable bars, means for locking said bars against removal with respect to an opening to be guarded, said means including a cross member, and an interlocking arrangement on said bars and cross-member.

15. A grating made up of removable bars, means for locking said bars against removal with respect to an opening to be guarded, said means including a cross member having a portion of an interlocking arrangement formed thereon.

16. A grating made up of removable bars, means for locking said bars, means for locking said bars against removal with respect to an opening to be guarded, said means including a cross-member having a plurality of notches formed therein.

17. In a window grating of the character described, in combination with grating bars, means for fixing said bars in relation to a window opening, said means including a casing and means in said casing for anchoring said bars to said casing, and means for reinforcing said bars, said reinforcing means including means for preventing relative longitudinal movement of said bars.

In testimony whereof I affix my signature.
IRVING KEMP.
